Frank Warren
ATTORNEY

UNITED STATES PATENT OFFICE.

JOHN F. HIELSCHER, OF SEATTLE, WASHINGTON
CLOCK-CONTROLLED ELECTRIC SIGNAL SYSTEM.

1,396,370.

Specification of Letters Patent.

Patented Nov. 8, 1921.

Application filed April 2, 1918. Serial No. 226,304.

To all whom it may concern:

Be it known that I, JOHN F. HIELSCHER, a citizen of the United States, residing at Seattle, in the county of King and State of Washington, have invented a certain new and useful Improvement in Clock-Controlled Electric Signal Systems, of which the following is a specification.

My invention relates to improvements in clock-controlled electric signal systems that are used in hotels, rooming houses and like places which signal systems shall embody mechanical devices for automatically controlling the operation of the call-bells or other signals, and the object of my invention is to provide a simple and efficient signal system that may be easily installed in a hotel, rooming house or like place that is wired for telephones or call-bells without making extensive changes in the already installed wiring.

A further object of my invention is to provide a signal system wherein an ordinary twelve hour clock may be utilized to drive the mechanical device that automatically controls the operation of the bells or signals.

A still further object of my invention is to provide controlling devices for a signal system that are neat and compact in appearance and easy to understand and operate.

My invention consists in the novel construction, adaptation and combination of parts as will be more clearly hereinafter described.

I accomplish these objects by devices illustrated in the accompanying drawings, wherein—

0 Figure 1 is a wiring diagram illustrating my invention, plan views of certain controlling devices being shown in association with such diagram;

Fig. 2 is a plan view of a mechanically actuated circuit closing device embodied in my invention; and

Fig. 3 is a view in cross-section substantially on broken line 3, 3 of Fig. 2.

While the drawings illustrate the installation of my signal system for two rooms only, it will be readily seen that the same system may be extended to include any desired number of rooms by a simple duplication of parts.

Referring to the drawings throughout which like reference numerals indicate like

parts, the numerals 5 and 6 indicate electric call-bells that may be disposed in the rooms of a building, as a hotel, and 7 and 8 indicate dials that may be disposed in a central station, as the office of a hotel, and are each graduated or divided around their peripheries into twenty-four equal spaces which correspond to the twenty-four hours of a complete day and are preferably numbered like a twenty-four-hour clock dial.

The upper half of each of the dials 7 and 8 is marked to indicate the day, beginning at six o'clock in the morning and ending at six o'clock in the evening; and the lower half of each of the dials 7 and 8 is marked to indicate the night, beginning at six o'clock in the evening and ending at six o'clock in the morning.

The dials 7 and 8 may also be marked in a convenient manner to indicate the rooms with which they are connected, as for instance, the dial 7 is marked "Room 1" to indicate that it is connected with "Room 1" and the dial 8 is marked "Room 2" to indicate that it is connected with "Room 2."

In the peripheral portions of the dials 7 and 8 whereon the subdivisions of time occur, there are provided electrical contacts or terminals, which may be made at each hour mark and at as many points as desired between the adjacent hour marks.

Pivotedly secured to the centers of the dials 7 and 8 are contact arms 10 and 11, respectively, whose outer ends are adapted to make electrical contact with the contact members 9 as the contact arms 10 and 11 are moved over the dials 7 and 8.

The contact arm 10 on the dial 7 is connected with an oscillating switch arm 35 that may be electrically connected with the bell 5 by a current wire 12 and the contact arm 11 on the dial 8 is connected with another oscillating switch arm 36 that may be electrically connected with the bell 6 by a circuit wire 13, so that the contact arms 10 and 11 form switch blades for closing an electrical circuit between the bells 5 and 6 and any desired one of the terminals 9 on the peripheral portions of the dials 7 and 8.

14 is a mechanically actuated contact making device comprising a dial 15 that is similar to the dials 7 and 8 and has its face near the peripheral edge subdivided into twenty-four spaces corresponding to the twenty-four hours of a complete day.

Arranged around the periphery of the

2
dial 15 at each hour point and at as frequent intervals between the hour points as desired, are electrical contact members or terminals 16 that are each connected by suitable electrical circuit wires with corresponding terminals on each of the dials 7 and 8 as more clearly hereinafter described.

Secured on a post 17 in the center of the dial 15 is a contact arm 18 that is adapted to be moved around the face of the dial 15 to successively make contact with the various terminals 16.

20 is an electrical circuit wire that connects the post 17 with one terminal of a battery 21, the other terminal of the battery 21 being connected by a circuit wire 22 with the bells 5 and 6.

As previously stated, each of the terminals 16 on the dials 15 is connected with corresponding terminal 9 on the dials 7 and 8 but for the purpose of illustrating my invention and avoiding confusion only four of the circuit wires connecting these respective terminals are shown in the drawings, namely circuit wires 23 and 24, respectively, connecting the ten and eleven o'clock morning terminals and circuit wires 25 and 26, respectively, connecting the four and five o'clock morning terminals on the dials 15, 7 and 8.

From the above description it will be seen that the arrangement is such that when the contact arms 10 and 11 are set on any of the contacts 9 of the dials 7 and 8 an electrical circuit will be closed by the contact arm 18 when it reaches a corresponding terminal on the dial 15.

For the purpose of moving the contact arm 18 completely around the dial 15 once in twenty four hours, the post 17 upon which such contact arm is mounted is connected by means of a large gear 27 and a small idler gear 28 with a small driven gear 29 on the hour shaft 30 of an ordinary twelve hour clock, which may be disposed in a casing 31, the mechanism of the clock not being shown.

The ratio of the gears 27, 28 and 29 is such that two complete revolutions of the shaft 30 are required to make one complete revolution of the shaft 17.

50 The idler gear 28 is used for the purpose of making the larger gear wheel 27 travel in the same direction as the small gear wheel 29.

55 The gear wheels 27, 28 and 29 may be mounted in any suitable frame 32 and the dial 15 may be secured on the top of such frame 32.

If desired, a twelve hour clock dial 34 may be placed on the frame 32 so that the device may be used as an ordinary clock.

The oscillating contact member 35 is pivoted as at 37 and is normally adapted to make contact with a terminal 38 of a conductor wire 39 that is connected with a bell

5, as shown by the broken line position in Fig. 1, so that a circuit is ordinarily completed between the bell 5 and the contact arm 10.

After the bell 5 starts to ring the occupant of "Room 1" may stop it by pressing downwardly on a button 40 on the end of the member 35 thus breaking the contact with the terminal 38, cutting out the bell 5 and making contact with another terminal 75 41 that is connected through the winding of a magnet 42 with the conductor wire 22.

When contact is made to attract the armature 43 on the contact member 35, the contact member 35 is held in the position shown 80 by full lines in Fig. 1, during which time the current is passing through the wires 12 and 22.

As soon as the contact arm 18 is moved off of the terminal 16 with which it has made 85 contact to ring the bell 5 the circuit through the wires 12 and 22 will be broken, the magnet 42 will release the armature 43, and the action of gravity due to the weight of the armature 43 will move the contact member 90 35 into position shown by broken lines in Fig. 1, so that when the contact arm 18 again completes a circuit through the wires 12 and 22 the bell 5 will be rung.

The operation of the oscillating switch 95 arm and associated magnet and contacts that are connected with the bell 6 and with all other bells of the system are the same as the operation of the similar parts that are connected with the bell 5.

100 The operation of my clock-controlled electric signal system is as follows: If the person occupying "Room 1" wishes to have a call at five o'clock in the morning, the contact arm 10 on the dial 7 is placed on the five o'clock morning terminal and when the contact arm 18 on the dial 15 makes contact with the five o'clock morning terminal of the battery 21 through the wire 20, contact arm 18, wire 26, contact arm 10, wire 12, contact member 35, wire 39, bell 5 and wire 22, back to the other terminal of the battery 21, thus 11 ringing the bell 5 in "Room 1."

In a similar way the bells in any room may be rung at any desired predetermined time.

The terminal 16 and the point of the contact arm 18 are of such size that it will require about one minute for the contact arm to move entirely across the terminals, thereby causing the bells to be rung for a period of about one minute unless they are shut off by movement of the switch arms 35 and 36.

If my device is used in a hotel where a separate system of return call signals are provided between the rooms and the office the cut out mechanism comprising the oscillating contact members and magnet may be dispensed with and the clerk may stop the ringing of the bell by moving the contact

arm on the dial 7 or 8 off of the terminal on which it is resting as soon as he gets a return signal from the room in which the bell is ringing.

5 The use of my system in hotels obviates the necessity of the clerk being on duty at all times for the purpose of calling the various rooms as required.

It will be readily seen that the signal system may be connected with the ordinary bell signal system of a hotel or with the telephone system or with any other system that provides two circuit wires from the rooms to the office, the only extra wiring that will be required to install this system being the wiring that will be necessary in the office.

Manifestly, changes may be made in the forms, dimensions and arrangement of parts of my invention without departing from the spirit thereof.

What I claim is:

In combination, a signaling system including indicating dials having spaced graduations forming contacts thereon to indicate

the hours of a day, contact-arms pivoted to and movable over the dial, an electric circuit, an alarm for each dial, said alarm being connected to said circuit, pivoted oscillating switch arms for each dial and alarm and located in said circuit, said switch arm being normally in circuit between the indicating dials and said alarm, a circuit-closing dial located in said electric circuit and coöperating with said first-named dials and switch arms to complete an electric circuit, a magnet interposed between each alarm and dial, said magnet being normally held out of said electric circuit, a second circuit extending from said magnet to said switch dial, and means carried by said oscillating switch arms to cause the energizing of said magnet to complete a circuit through said second circuit and switch dial for breaking the circuit between the indicating dials and said alarm.

In witness whereof I hereunto subscribe my name this 26th day of March, A. D. 1918.

JOHN F. HIELSCHER.
